DESCRIPTION

FIG. 1 is a perspective view of a storage rack showing my new design;

FIG. 2 is a front elevational view of the vehicle storage rack of FIG. 1;

FIG. 3 is a rear elevational view of the vehicle storage rack of FIG. 1;

FIG. 4 is a bottom plan view of the vehicle storage rack of FIG. 1;

FIG. 5 is a top plan view of the vehicle storage rack of FIG. 1; FIG. 6 is a left side elevational view of the vehicle storage rack of FIG. 1; and,

FIG. 7 is a right side elevational view of the vehicle storage rack of FIG. 1.

In the drawings, the broken lines show portions of a vehicle storage rack that form no part of the claimed design.
